UNITED STATES PATENT OFFICE.

HARRY S. LEE, OF SYRACUSE, NEW YORK.

BOTTLE CLOSURE.

Application filed October 6, 1925. Serial No. 60,880.

This invention relates to bottle closures, designed for use in connection with bottles and jars commonly employed for serving and dispensing milk, cream, and the like, for 5 household and other uses.

My invention has especial reference to the class of bottle closures shown and described, for example, in United States Patent No. 919,937, dated April 27, 1909, wherein a 10 hood-like cap, such as paper, or other non-metallic material is snugly fitted to and overlays the top of the bottle, and also a portion of the neck below the usual beaded mouth, and supplements the well-known disc stopper, which is tightly applied to the sunken seat that surrounds the mouth of the ordinary milk bottle.

The present invention relates particularly to improvements in the fastening devices 20 shown and described in my pending application, Serial No. 40,371, filed June 29, 1925.

The object of the present invention is to provide a cheap, light, stout, pliable fastener or tie, which preferably comprises a flat 25 woven flexible tape or band, or may consist of any suitable cotton or other twine, that may be tightly wound around the portion of the bottle neck that is overlaid with the snug fitting hood, and then securely tied by means 30 of a knot, for preventing removal or loosening of the hood, without showing that the skirt has been tampered with. The knot by which the loose ends of the tape are secured, in the present case, preferably comprises 35 one, two or four loops or bows, instead of the plain "square" knot of my pending application, and in order to render such bow-knot effective for preventing unauthorized untying or loosening of the tape, after the completing 40 of the tying operation, the projecting loops or bows, as well as the loose ends of the tape are cut or sheared adjacent the body of the knot, for providing a number of relatively short radial ends, simulating a rosette, which 45 if tampered with tend to destroy the binding effect of the fastener, and the said cutting or trimming of the loops and ends furthermore result in the shortening of the tape to such extent that it is impossible to 50 retie the fastener.

The various features and parts of the invention will be understood from the detailed description which follows, and by reference to the accompanying drawings, in which—

55 Figure 1 is a broken elevation and partial section of a milk bottle whose mouth is

closed by a fibrous hood, to which my improved fastener is applied; showing the loops of a double bow-knot clipped or trimmed. Fig. 2 is a similar view; showing the tape 60 tied with a double bow-knot ready for the final shearing or trimming operation. Fig. 3 is a side elevation, showing the fastening tape tied in a manner to provide four loops or bows. Figs. 4, 5 and 6, show respectively 65 diagrammatic views of single, double and quadruple bow-knots; the full lines in said views showing the respective knots after the loops and loose ends have been trimmed. And Fig. 7 is a reduced plan view of the disc 70 from which the hood is formed.

In the drawing, 2 represents the body of an ordinary milk bottle or container, such as commonly used for serving milk and cream to customers. 3 is the neck of the bottle, 75 whose top is formed with the usual annular bead 4, that surrounds the mouth 5; the latter being formed with a depressed annular socket or seat 6, to receive the well-known disc stopper 7. 8 represents a hood-like external closure or cap, which is usually made of a tough flexible variety of paper, the said cap being ordinarily furnished to the bottlers in the form of a disc, as 8' (see Fig. 7) 80 which is applied to the top of the bottle (see Figs. 1 and 2) immediately after the bottle is filled and sealed by means of the stopper 7. The central portion 8^a of the disc 8' overlays the mouth of the bottle, parallel to the stopper 7, and after the adjacent medial portion is molded around the bead 4, the margin of the disc is compressed and molded against the neck 3 below the bead, for forming a contracted snug fitting skirt 8^b. Where no other fastening means are employed, the 85 skirt 8^b is usually pasted or otherwise secured to the neck, by paraffin or other suitable temporary adhesive (not shown). In practice, it has been found that the more or less rough handling of the bottles by the deliverymen, tends to loosen the lightly pasted skirts 8^b, and in some cases the hoods are tampered with, either for the purpose of substituting the contents of the bottles, or for making unauthorized use of the same. These troubles 90 have heretofore been overcome by various means, such for example, as by winding about the neck 3 a wire, or by applying a rubber band of suitable tension to hold the skirt in place, as shown at 12 in the afore- 95 mentioned patent. Still another means for securing the skirt in place is shown in my 100 105 110

co-pending application, wherein a flat flexible band or tape, is wound around the skirt, and is then tied by means of a "square" knot, after which the free ends of the tape are overlapped and securely stitched or sewed, for preventing tampering with the knot. This sewing of the loose ends of the fastener requires the employment of a more or less complicated and expensive sewing mechanism, which not only greatly increases the cost of sealing the bottles, but also prolongs the work of preparing the bottles for delivery. In the present case, the fastening means preferably comprises a similar flat flexible non-elastic tape, as 9, which may be readily and quickly coiled around the portion of the neck 3 that is overlaid by the skirt 8^b, after which the ends of the tape are tied, first with a single knot, and then formed with double loops or bows, as 9'-9^a and two loose ends, as 9^b-9^c, all of which parts are finally drawn tight in the usual manner, as shown in Fig. 2. The tape 9 employed for securing the skirt 8^b, is usually wound upon a spool (not shown), from which the tape is fed continuously into the tying machine, and after each tying operation, the wound and tied portions of the tape are severed, as shown at α in Fig. 2, by any suitable shearing mechanism (not shown). At this stage of the binding and fastening of the skirt 8^b, according to Fig. 2, the knot comprises two loops 9'-9^a and the resultant free ends 9^b-9^c. If the fasteners were left in this condition, the tape 9 might be readily untied by simply pulling on the loose ends 9^b-9^c, in a well-known manner, and the cap 8 might then be readily removed and the contents of the bottle tampered with or used, and the said parts might be afterwards replaced and the tape again tied, without danger of detection. In order to provide against such unauthorized unfastening and removing of the cap 8, and the retying of the tape 9, the bottling machine is preferably equipped with suitable means (not shown) for clipping or shearing the several loops 9'-9^a, as well as the loose ends 9^c-9^b of the bow-knot, preferably at the points indicated by the broken lines 9^d in Figs. 2 and 3. This shearing of the loops and ends of the tape leaves the knot in the condition shown in Fig. 1, and by the full lines in Fig. 5, wherein six relatively short loose ends or arms, as 9^b, 9^c and 9^x, are shown radiating from the central body 9^e of the knot. By this construction and arrangement of the knot, any attempt to loosen the tape 9, as by pulling on the said arms or strands, will result in withdrawing all but two of the

arms effected by the shearing, thereby leaving the knot so loosely tied that the tape 9 may be readily slipped downwardly bodily and freed from the skirt 8^b. The cap 8 may then be removed and the contents of the bottle withdrawn by simply displacing the stopper 7. The shearing of the loops and loose ends of the knot so shortens the tape that the latter cannot again be coiled around the skirt 8^b and tied in a manner to present to the accustomed eye a knot having six radial arms, for example, as shown in Figs. 1 and 5. In practice, the milk vendors usually adopt a knot having one, two or four loops or bows, and their customers are able by means of visual inspection to instantly detect any tampering with the hood fastening means, as described.

In Figs. 3 and 6 the knot is shown formed with four loops, as 10, 10', 10^a and 10^b, and when the loops and arms 10^c-10^d are sheared on the broken lines 9^d, ten ends or arms radiate from the body of the knot, as shown diagrammatically in Fig. 6, and present a rosette appearance. Any attempt to loosen the knot, as by pulling on the several arms, will result in withdrawing all but two of the said arms, and correspondingly loosening the knot, and rendering the tape incapable of being retied, without showing mutilation of the rosette and therefore indicating tampering.

Having thus described my invention, what I claim, is—

1. A combined fastener and means for indicating unauthorized tampering with the protective wrapper of an article comprising a pliable tape, the ends of the tape being tied by means of a bow-knot and the bows being sheared for providing a plurality of radiating arms in addition to the normal free ends of the tape, and the shearing of said bows effecting a substantial shortening of the tape adapted to prevent replacing of the fastener and restoring of the tape to the wrapper in case the knot is untied.

2. A combined fastener and means for indicating unauthorized tampering with the protective wrapper of an article composed of a band having ends tied by means of a plurality of bow-knots so as to leave the ends loose, the bows being sheared to provide additional loose ends, the ends being all arranged to conjointly simulate a rosette signifying authorized sealing of the article and being of such length so as to prevent retying and restoring of the rosette.

In testimony whereof I affix my signature.

HARRY S. LEE.
